UNITED STATES PATENT OFFICE.

AVERY H. THOMAS, OF HOUSTON, TEXAS, ASSIGNOR TO HOUSTON PUMP & SUPPLY COMPANY, OF HOUSTON, TEXAS, A CORPORATION OF TEXAS.

ELEVATOR.

Application filed August 29, 1921. Serial No. 496,742.

To all whom it may concern:

Be it known that I, AVERY H. THOMAS, a citizen of the United States, residing at Houston, Harris County, Texas, have invented a certain new and useful Improvement in Elevators, of which the following is a full, clear, and exact description, such as will enable others skilled in the art to which it appertains to make and use the same.

10 My invention relates to elevators for use in well drilling and pumping. It has particular reference to elevators used in handling pipe, casing, tubing, drill stem, etc., when said pipe is being introduced into the well or when it is being removed therefrom.

15 The object of my invention is to provide an elevator for handling pipe which will be resiliently supported so as to withdraw a portion of the pipe a short distance when it has been detached from the string of pipe in the hole.

20 Another object is to provide an elevator which will prevent the wearing and mutilation of the threads at the joints when the sections of pipe are unscrewed and detached from the rest of the string.

25 Another object is to so mount my elevator that it may turn about a vertical axis, thus avoiding the necessity of a separate swivel.

30 These and various other objects and advantages are accomplished by a certain combination and relation of parts, the preferred embodiments of which are disclosed in the drawing herewith, wherein like numerals 35 of reference are applied to like parts in all the views, as far as is possible.

In the drawing Fig. 1 is a front elevation of my invention, the upper part of which is shown partly in central longitudinal section.

40 Fig. 2 is a transverse section on the plane 2-2 of Fig. 1 looking upward. Fig. 3 is top plan view of the upper yoke in Fig. 1, and Fig. 4 is a modification of my invention.

45 My pipe elevator is shown assembled in Fig. 1. There is a grappling block 1 having a pipe receiving recess 2 therein, this recess being adapted to be closed by a latch 3. This block has laterally extending trunnions 4, furnishing a pivotal attachment for the lower ends of a U-shaped bail 5.

50 The upper end of the bail 5 is extended upwardly to form a cylindrical post 6, threaded at its upper end to receive a nut 7. Toward the lower end of the post 6 is a 55 slidable yoke 8. It has a central opening

9 to receive the post and two lateral trunnions to pivotally receive the lower ends of a short bail 11, the said ends of which have openings into which said trunnions are adapted to fit.

60 Below the yoke 8 is a ring 12 fixed to the post. The upper face of said ring is grooved to provide a track for a ball race 13 thereon. Between this ring and the yoke is a washer 14 upon which the yoke will rest when the weight is released from the elevator block 1.

65 Immediately below the nut 7 is a plate 15 70 slideable on the post 6 and having laterally extending forked ends which straddle the arms of the bail 11 and prevent rotation of said bail relative to the plate.

75 Between the plate 15 and the yoke 8 is a spiral spring 16 acting to force said plate and yoke apart and thus furnish a resilient connection between the bail 11 and the 80 bail 5.

85 Thus when the upper bail 11 is secured to the travelling block in the derrick, the weight of the elevator, and the pipe suspended therein, acts to pull the post 6 downwardly through the yoke 8 and compress the spring 16. I contemplate so calibrating the power of this spring that it will withstand, with only slight compression, the weight of several joints of tubing or pipe, such as is being handled. The force of the spring will thus act to raise the joints of tubing released from the string in the hole. Ordinarily when a string of pipe is being removed from the hole, the elevator is secured about the 90 upper end thereof and the string is lifted to expose several joints of pipe, say three lengths thereof. The string of pipe is then supported near the derrick platform, by the rotary, or casing head as the case may be, 95 and the upper lengths are unscrewed and, when detached, are lifted and set aside on the platform. In unscrewing the joint with the ordinary type of elevator the weight of the joints released either rests on the coupling where the unscrewing takes place, or is held upward with great force by the cable.

100 Either way it is handled, the threads at the coupling will be liable to mutilation, due to careless handling. Furthermore, when the upper sections are unscrewed it is necessary to start the hoisting drum to raise the pipe so as to set it over and stand it on the derrick platform.

With the use of my elevator, the pipe is

raised and the string allowed to rest in the rotary or casing head and the travelling block and elevator are raised only such distance as is necessary to compress the spring 16. The pipe is then unscrewed at the coupling and when fully disconnected, the force of the spring will be sufficient to raise the unscrewed sections away from those remaining. The force will not be sufficient, however, to break the threads nor will the pipe after unscrewing, rest on the coupling to mutilate the threads by the weight of the pipe above. The further advantage will be that, it will not be necessary to start the draw works to raise the pipe to set the detached sections aside, but the spring will itself raise the pipe sufficiently to allow it to be swung over and stood on the derrick platform.

It will also be noted that my device has a swivel action, making it unnecessary to employ the usual swivel connection with the travelling block. To facilitate this swivel action a ball race 17 is formed between the plate 15 and the lower face of the nut 7. This will allow the post 6 and nut 7 to rotate relative to the bail 11, plate 15 and yoke 8, without resistance, the upward thrust of the spring 16 being taken up in the anti-friction bearing formed by the ball race 17. The ball race 13 allows free rotation thereon when the load is released.

In Fig. 4 I have shown a different embodiment of my resilient mounting. Here the trunnion 4 of the elevator block 1 is supported in a semicylindrical recess in the upper face of a block 18, fitting slidably within an elongated slot 19 in the lower end of the bail 5. The block 18 is held resiliently up-

ward by means of a spring 20, bearing at its lower end on the end of the slot 19. This spring is calibrated to support a load similar to that of spring 16 previously described. The operation and advantages of this construction are similar to those of the preferred embodiment, but the elevator does not have the swivel action as will be obvious.

Having thus described my invention, what I claim as new and desire to protect by Letters Patent is:

1. In an elevator, the combination of a pipe clamping block, a post thereon, a yoke slidable on said post, a bail on said yoke, a stop nut on said post above said yoke, a spring on said post between said yoke and said nut and means to hold said bail erect relative to said post.

2. In an elevator, the combination of a pipe clamping block, a supporting means therefor including an upwardly extending post, a yoke slidable thereon, a bail on said post, a stop nut at the upper end of said post, a spring between said yoke and said stop nut, acting to force said nut and yoke apart, and a plate on said post, acting to hold said bail erect.

3. In an elevator, the combination of a pipe-clamping block, lateral trunnions thereon, a supporting means comprising a single bail, secured to said trunnions, an upwardly-extending post on said bail, a yoke slidable on said post, a resilient connection between said yoke and said post, and supporting means for said yoke.

In testimony whereof, I hereunto affix my signature this the 26th day of July, A. D. 1921.

AVERY H. THOMAS.
